UNITED STATES PATENT OFFICE.

DOMINICK PELLETIER, OF FALL RIVER, MASSACHUSETTS.

PRESSER.

Application filed April 1, 1924. Serial No. 703,456.

To all whom it may concern:

Be it known that I, DOMINICK PELLETIER, a citizen of the United States, residing at Fall River, in the county of Bristol and 5 State of Massachusetts, have invented certain new and useful Improvements in Pressers, of which the following is a specification, reference being had to the accompanying drawings.

10 This invention relates to certain improvements in pressers and has relation more particularly to a device of this general character especially designed and adapted for use in pressing neckties or the like and it is 15 an object of the invention to provide a device of this general character embodying novel and improved means whereby the desired result is accomplished through the medium of a single compression.

20 The invention consists in the details of construction and in the combination and arrangement of the several parts of my improved presser whereby certain important advantages are attained and the device 25 rendered simpler, less expensive and otherwise more convenient and advantageous for use, as will be hereinafter more fully set forth.

The novel features of my invention will 30 hereinafter be definitely claimed.

In order that my invention may be the better understood, I will now proceed to describe the same with reference to the accompanying drawings, wherein:—

35 Figure 1 is a view in perspective illustrating a presser constructed in accordance with an embodiment of my invention and in working assembly;

40 Figure 2 is a view in perspective of one of the members comprised in the presser;

Figure 3 is a view in perspective of the second member comprised in the presser;

45 Figure 4 is a longitudinal vertical sectional view taken through the structure as illustrated in Figure 1.

As herein disclosed, my improved presser comprises an elongated body member 1 of requisite dimensions and substantially conforming to the end portion of a necktie, the upper or working surface or face of said member 1 being smooth and unobstructed. The member 1 inwardly of each end has operatively engaged therewith a lever L.

50 As herein disclosed, the lever L is formed of a single strand of wire of requisite gauge and substantially U-shaped in form with

the extremities of the side members *a* thereof inwardly disposed, as at *b*, and freely insertible within the recesses 2 formed in the side or edge faces of the member 1. The 60 central portion of the intermediate part *c* of the lever L is pinched or otherwise formed to provide an outstanding handle member 3 whereby the requisite swinging movement 65 may be imparted to the lever L.

Adapted to be superimposed upon the member 1 is a second member 4 of substantially the same configuration as the member 1 and having its inner or working face smooth and unobstructed. The outer face 70 of the member 4 inwardly of its opposite ends has disposed thereacross the outstanding blocks 5, the outer face *d* of each of said blocks being rounded transversely. Overlying and slightly disposed above the 75 rounded face of each of the blocks 5 are the side arms *e* of a substantially U-shaped resilient catch 6, the extremities of said side arms *e* being embedded within the member 4 at a point immediately adjacent the low 80 edge of the associated block 5.

As is clearly illustrated in Figure 2 the resilient catch 6 extends beyond the block 5, and it will be apparent that by inserting an implement such as a screw-driver or the like 85 between the catch and block and exerting requisite pressure toward the larger end of the member 4 the catch 6 will be forced home.

The end portion of a tie to be pressed is 90 inserted between the members 1 and 4 with the member 4 bridged by the levers L. The levers L as herein disclosed are swung toward the larger ends of the members 1 and 4 so that the intermediate portion of said 95 levers L will have close contact with the side arms *e* of the members 6 and thereby effectively clamp the tie between the members 1 and 4 and exert the requisite pressure thereon. In order to prevent the levers L from 100 slipping into release position, the upper portions of the side arms of the members 6 are notched, as at 8, or otherwise roughened.

While I have herein disclosed a presser constructed in accordance with an embodiment of my invention with a plurality of levers L, it is to be understood that in connection with the smaller work a single lever L can be used.

From the foregoing description it is 110 thought to be obvious that a presser constructed in accordance with my invention is

particularly well adapted for use by reason of the convenience and facility with which it may be assembled and operated, and it will also be obvious that my invention is 5 susceptible of some change and modification without departing from the principles and spirit thereof and for this reason I do not wish to be understood as limiting myself to the precise arrangement and formation of 10 the several parts herein shown in carrying out my invention in practice except as hereinafter claimed.

I claim:—

1. A presser of the class described comprising lower and upper pressing boards of substantially the same configuration, the upper board being provided upon its outer face with a transversely extending block having its outer face rounded, a U-shaped 15 catch secured to the upper board and overlying the outer face of the block, and a U-shaped lever pivotally engaged with the lower board and bridging the upper board, said lever when swung in one direction engaging the catch and exerting pressure upon the block to force the boards together.

2. A presser of the class described comprising lower and upper pressing boards of substantially the same configuration, the upper board being provided upon its outer face with a transversely extending block having its outer face rounded, a resilient 30 U-shaped catch secured to the upper board and slightly disposed above and conforming 35 to the face of the block, and a U-shaped lever pivotally engaged with the lower board and bridging the upper board, said lever when swung in one direction engaging the catch and exerting pressure upon the block to 40 force the boards together.

3. A presser of the class described comprising lower and upper pressing boards of substantially the same configuration, the upper board being provided upon its outer face with a transversely extending block 45 having its outer face rounded, a resilient U-shaped catch having its extremities bent back and embedded within the upper board immediately adjacent the lower edge of the block, said catch being disposed slightly 50 above and conforming to the face of the block and having its side arms roughened, and a U-shaped lever pivotally engaged with the lower board and bridging the upper 55 board, said lever when swung in one direction engaging the catch and exerting pressure upon the block to force the boards together.

4. A presser of the class described comprising lower and upper pressing boards of substantially the same configuration, the upper board being provided upon its outer face with a transversely extending block having its outer face rounded, a resilient 60 U-shaped catch having its extremities bent back and embedded within the upper board immediately adjacent to the low point of 65 the rounded face of the block, said catch being disposed slightly above and conforming to the face of the block and extending beyond the block, and a U-shaped lever pivotally engaged with the lower board and bridging the upper board, said lever when 70 swung in one direction engaging the catch and exerting pressure upon the block to 75 force the boards together.

In testimony whereof I hereunto affix my signature.

DOMINICK PELLETIER.
